T. Shaw, Inventor

UNITED STATES PATENT OFFICE.

THOMAS SHAW, OF PHILADELPHIA, PENNSYLVANIA.

SIGNAL-TUBE FOR MINES.

SPECIFICATION forming part of Letters Patent No. 390,262, dated October 2, 1888.

Application filed October 8, 1887. Serial No. 251,846. (No model.)

To all whom it may concern:

Be it known that I, THOMAS SHAW, of the city and county of Philadelphia, Pennsylvania, have invented a new and improved Signaling-Tube; and I hereby declare the following to be a full, clear, and exact description of the same, reference being had to the accompanying drawing, and to the letters of reference marked thereon.

10 The object of my invention is to produce a signal device adapted to convey signals long distances; and my invention consists in a metallic sound-conductor, preferably in the form of a metal tube, suspended or supported upon 15 flexible or elastic supports and provided with sound concentrators or intensifiers, whereby signals produced at one end of the metal sound-conductor may be distinctly heard at the other distant end.

20 In more particularly describing my invention reference is made to the accompanying drawing, which represents a vertical section of a mine-shaft supplied with my invention.

My invention consists, first, in supporting a 25 metallic sound-conductor, preferably in the form of an iron or steel tube, upon elastic or flexible supports, and, secondly, in the use of sound concentrators or intensifiers.

The shaft *a* has a gangway running to a heading, *c*, and a conductor, *d*, in the form of an iron tube, is located (suspended by flexible suspensors *e*, such as flexible loops of cord or metal) at various points throughout its length. Where any great strain is put upon the supports, a bed or bearing of elastic material, as rubber, is substituted for the flexible suspensors, as at *f* on the ground-surface, where the weight of the conductor rests on the elastic bearing. The end of the tube at the upper 40 station is provided with any suitable sound-amplifier, *h'*, as a tuning-fork, bell, or metal disk, capable of producing a tone not discordant with that resulting from the vibrations of the metal tube, and this device *h'* is bolted in 45 any suitable manner to the tube.

A sound-concentrator, in the form of a metal gong or bell, *h*, is provided adjacent to each intensifier *h'*, to permit the ear to be rested upon or placed near said concentrator-bell, 50 which will concentrate the sound, so as to prevent interference of sounds from other sources

with the sounds coming from the metal pipe. The end of the conductor at the lower station in heading *c* is similarly provided with a sound-intensifier and sound-concentrator.

55

It is a very common thing to convey sound within narrow limits of three, and possibly five, hundred feet by striking a metallic conductor with any hand object; but when the conductor extends for a half mile or over, all 60 vibrations are absorbed and no sound is conveyed to the end.

When the conductor is supported by yielding or elastic bearings or supports throughout its length, it will effectually convey sounds for 65 over a mile, and these sounds are rendered more sharp, distinct, and audible by the addition of intensifiers secured at each end of the conductor, especially if tubular, while the concentrators enable all sounds transmitted to be 70 readily received.

It will be observed that the essential characteristics of my device consist of a rigid metallic conductor, which is freely supported throughout its length, and not under tensile 75 strain, and which conveys the sound by vibrations within itself in contradistinction to the longitudinal vibrations in a wire or conductor held under strain at its end, as in the well-known mechanical telephones.

80

The said invention is an excellent auxiliary to the device set forth in my patent, No. 359,102, for test and signal apparatus for mine use.

In some cases the concentrators or intensifiers alone may be used in connection with the 85 conductor.

What I claim, and desire to secure by Letters Patent, is—

1. A mine signaling device consisting of a continuous rigid metallic conductor having its 90 ends freely supported and suspended by yielding supports throughout its length and extending into the mine through the shaft and between the points of communication, substantially as described.

95

2. A mine signaling device consisting of a rigid continuous metallic conductor having freely-supported ends and suspended on yielding supports throughout its length, one end extending into the mine through the shaft and 100 provided at the ends with sound-intensifiers, substantially as described.

3. A mine signaling device consisting of a rigid continuous metallic conductor having freely-supported ends and suspended on yielding supports throughout its length, one end extending into the mine through the shaft and provided at the ends with sound intensifiers and concentrators, substantially as described.

4. A mine signaling device consisting of a rigid metallictubular conductor having freely-supported ends and suspended on yielding

supports throughout its length, one end extending into the mine through the shaft and provided at both its ends with sound intensifiers and concentrators, substantially as described.

THOMAS SHAW.
